UNITED STATES PATENT OFFICE.

CARLOS STRICKHouser, OF PHILADELPHIA, PENNSYLVANIA, ASSIGNOR TO
FRIEDBERGER-AARON MANUFACTURING COMPANY, OF PHILADELPHIA,
PENNSYLVANIA, A CORPORATION OF PENNSYLVANIA.

DESIGN FOR LACE EDGING.

47,765.

Specification for Design. **Patented Aug. 24, 1915.**

Application filed June 9, 1915. Serial No. 33,188. Term of patent 7 years.

To all whom it may concern:

Be it known that I, CARLOS STRICKHouser, a citizen of the United States, residing in Philadelphia, county of Philadelphia, and State of Pennsylvania, have invented a new, original, and ornamental Design for Lace Edging, of which the following is a specification, reference being had to the accompanying drawings, which form a part thereof.

The drawing is a plan view of a portion of lace edging showing my design.

The same comprises a tip or border of peculiar configuration the marginal loops of which form parts of elliptical shaped rings

which extend within the tip or border and unite the same with the opposite sewing-on edge.

I claim:

The ornamental design for lace edging, as shown and described.

In testimony of which invention, I have hereunto set my hand, at Philadelphia, on this 8th day of June, A. D. 1915.

CARLOS STRICKHouser.
